HIGH FREQUENCY SYSTEM

Alfred Wiessner, Berlin, Germany, assignor to
C. Lorenz Aktiengesellschaft, Berlin-Tempelhof,
Germany, a company

Application April 13, 1938, Serial No. 201,715
In Germany April 13, 1937

4 Claims. (Cl. 179—91)

The present invention relates to high frequency systems, and more particularly to selector rack arrangements in such systems as generally employed in telephone exchange stations.

It is well known to effect intelligence transmission by means of high frequency carrier currents, and to impress a plurality of carrier waves upon the telephone lines in an exchange station. Systems of the above mentioned type require the provision of electric separating filter devices so as to permit the high frequency and the low frequency message currents to be impressed upon the transmission channel common thereto. It has been suggested in the past to employ specific racks adapted to receive particular groups of electric separating filters, which consist of suitably interconnected capacities and inductances, but this expedient introduces certain disadvantages since it will be hardly possible on account of the restricted space conditions in ordinary exchange offices to stow the great number of wires required for interconnecting the lines and the electric filter devices.

The present invention has for its object to avoid the aforesaid difficulties by arranging the filter devices directly in the selector racks and in close proximity to the appertaining sets or groups of selector switches and relays, so as to permit connecting wires of short lengths to be used.

The invention will be more readily understood from the following description taken in conjunction with the accompanying drawing; in which:

Fig. 1 is a front elevation of an arrangement according to the invention; Fig. 2 is a side elevation of the arrangement shown in Fig. 1; while Fig. 3 shows a suitable wiring arrangement according to the invention.

In Figs. 1 and 2, 1 denotes a rack or frame carrying horizontal cross bars 4 which serve as support for 10 to 15 selector switches 2 and their pertaining sets of relays 3. The selector and relay sets or groups are attached to one side of the rack, while the lines 5 which are to be connected thereto are assembled to form bundles and arranged on the other side of the rack. One rack is adapted to receive a plurality of cross bars. According to a further feature of the invention, additional bars are fixed on the side remote from the side which carries the selector and relay sets, and these additional bars carry the electric separating filters 6 which act for applying the high frequency oscillations. One electric filter is allotted to each selector switch. The bundled high frequency and low frequency lines 5 are arranged

above the small boxes in which the electric filters 6 are placed.

The above described arrangement involves the advantage that the high frequency oscillations may be applied to existing racks or frames and, moreover, that the wiring in these racks will become extraordinarily simple. In addition, each filter device is fixed to its appertaining group or set of selectors and relays, an expedient which enables reliable supervision of the system and a considerably simplified wiring between the various elements.

The Fig. 3, by way of an example, illustrates the simple wiring conditions attained in accordance with the invention. The wires to the contacts *t* of the cut-off relay (not shown) which is allotted to the pre-selector circuits, are connected to the speech wires *a*2 and *b*2 of the final switch, and to the subscriber's line *a*, *b* at the terminal strips of the pre-selector frame. The wires which are extended to the subscriber's line over the main distributor are looped through an exchange filter by a simple wiring change. The lines *a*, *b* are associated with the output side of the electric filter and the high frequency oscillations are impressed over the conductors *a*1, *b*1.

What is claimed is:

1. In a telephone exchange system, selector switches arranged in groups, high and low frequency separating filters also arranged in groups corresponding to said selector groups, a plurality of two wire telephone lines arranged in groups corresponding to said switches and filters, each line having a filter associated therewith, a unitary supporting frame having a plurality of racks one for each of said groups of switches filters and lines, whereby each filter is mounted immediately adjacent the common connections between the associated selectors and lines.

2. In a telephone exchange system, pre-selector switches arranged in linear groups, control relays arranged in linear groups corresponding to said switches, high and low frequency separating filters arranged in linear groups corresponding to said switches and relays, a plurality of two wire telephone lines arranged in groups corresponding to said switches relays and filters, a unitary supporting frame having a plurality of racks one for each group of switches, relays filters and lines, whereby each filter is mounted immediately adjacent the corresponding switches relays and lines.

3. A telephone exchange system according to claim 2 in which the two wire lines and associ-

ated filters are mounted on one side of the associated supporting rack and the corresponding relays and selector switches are mounted immediately adjacent but on the opposite side of the rack.

4. In a telephone exchange system, a plurality of pre-selector switches, a plurality of two wire lines leading to said switches, a plurality of cut-off relays interposed between said lines and switches, a plurality of two wire lines leading from the first-mentioned line to final selectors, a plurality of subscriber's lines, a plurality of high and low frequency separating filters for said

subscriber's lines and through which the subscriber's lines are connected to the contacts of the associated cut-off relay, said subscriber's lines being connected to the low frequency output end of the associated filter, a high frequency line connected to the input of each filter, said lines filters relays and selectors being arranged in corresponding linear groups, and a unitary supporting frame having supporting racks for said lines filters relays and switches, whereby each filter can be mounted immediately adjacent the associated relays and pre-selector switches.

ALFRED WIESSNER.
